UNITED STATES PATENT OFFICE.

ROBERT A. PHILLIPS, OF TAYLORVILLE, ILLINOIS.

CORD-HOLDER.

1,252,300.

Specification of Letters Patent.

Patented Jan. 1, 1918.

Application filed August 22, 1916. Serial No. 116,321.

To all whom it may concern:

Be it known that I, ROBERT A. PHILLIPS, a citizen of the United States, residing at Taylorville, in the county of Christian and 5 State of Illinois, have invented certain new and useful Improvements in Cord-Holders, of which the following is a specification.

This invention relates to a cord holder and more particularly to a device for suspending 10 a cone or roll of twine or cord in a position directly above the table or counter where the cord may be within convenient reach.

The primary object of the invention resides in the provision of a pair of supporting hooks which may be suspended from the 15 ceiling or other suitable place of elevation and attached to the spool or cylinder upon which wrapping cord, twine or wire is usually wound.

20 As a further object of the invention the device comprises a pair of spring arms having their ends bent and sharpened to provide hooks for biting into the cylinder upon which the cord is wound, the resiliency of 25 the spring arms tending to hold the hooks in engagement with the cylinder.

A further object of this invention is the 30 provision of a cord holder which consists of comparatively few parts and is simple in construction, but durable and well adapted to withstand the rough usage to which devices of this character are ordinarily subjected.

For a full description of the invention and 35 the advantages and merits thereof, reference is to be had to the following description and the accompanying drawings, wherein is illustrated the preferred form of my invention, in which:

40 Figure 1 is a vertical longitudinal section through a roll of twine showing the same mounted upon the usual cylinder, and having my invention applied thereto.

Fig. 2 is a perspective view of the holder. 45 Referring to the drawing the numeral 1 designates the cop which is formed, in the usual manner, by winding the cord upon a hollow cylinder 2 so that a roll is formed which is slightly frusto-conical in forma-

tion. Since this is one of the most usual 50 methods of supplying wrapping cord, twine, wire and the like, it is thought advisable to illustrate the invention as being used in connection with this form of roll but it will be understood, of course, that the device may be 55 employed equally as well in connection with a ball of twine or any of the other usual methods of supplying the twine or cord to the trade.

The holder comprises the arms 3 and 4 60 which are spaced apart and curved toward each other at their upper ends to provide the U-shaped member 5 in the form of a pair of tongs. The arms 3 and 4 are relatively wide at their curved portions and gradually 65 tapered until the free ends of the arms terminate in a sharpened point or prong 6. The ends of the arms are then bent outwardly and curved to provide the pronged 70 hooks 7.

A supporting eye loop is formed of a circular ring integrally connected to the upper 75 ends of the arms and the ring is cut away at the point at which the ring joins the ends of the arms so that a space is provided for establishing communication between the U-shaped member 5 and the eye loop 8. The meeting ends of the arms are thus held 80 slightly spaced apart. The arms 3 and 4 are formed of any suitable spring material and 85 the curved portions of the arms are adapted to impart a resiliency so that each of the arms operates similar to a flat spring. An additional resiliency, however, is obtained by the eye loop 8 which, of course, is circular 90 in formation but is formed of the same material as the arms 3 and 4.

From the foregoing it will be observed 95 that a very simple and durable cord holder has been provided, the details of which embody the preferred form. I desire it to be understood however, that slight changes in the minor details of construction may be made without departing from the spirit of the invention or the scope of the claim hereunto appended.

I claim:

A holder for core wound cops comprising

a pair of arms, each arm being relatively wide at its upper end and curved to provide a resiliency for the arm, the said arms being tapered toward their free ends and terminating in points, the points being curved to provide hooked prongs, said point being adapted to engage said core.

In testimony whereof I affix my signature in presence of two witnesses.

ROBERT A. PHILLIPS.

Witnesses:

IDA BAYER,
ARTHUR YOCHE.
